US00D949558S

(12) **United States Design Patent** (10) **Patent No.:** **US D949,558 S**
(45) **Date of Patent:** **** Apr. 26, 2022**

(54) **SUITCASE**

(71) Applicant: **YETI Coolers, LLC**, Austin, TX (US)

(72) Inventors: **Derek G. Sullivan**, Austin, TX (US);
Steve Charles Nichols, Austin, TX (US);
Christopher Kalck, Austin, TX (US)

(73) Assignee: **YETI Coolers, LLC**, Austin, TX (US)

(**) Term: **15 Years**

(21) Appl. No.: **29/763,700**

(22) Filed: **Dec. 23, 2020**

(51) LOC (13) Cl. **03-01**

(52) U.S. Cl.

USPC **D3/279**; D3/289

(58) **Field of Classification Search**

USPC .... D3/203.1–203.2, 203.5–203.6, 206, 254, D3/263, 267–268, 272–273, 276, 279, D3/281–290, 294, 299, 301, 303, D3/318–319, 321, 327, 902 CPC .. (57)

CLAIM

The ornamental design for a suitcase, as shown and described.

DESCRIPTION

FIG. 1 is a front perspective view of a suitcase showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines immediately adjacent to the shaded area define the bounds of the claimed design and form no part thereof. The remainder of the broken lines depict portions of the suitcase that form no part of the claimed design.

1 Claim, 6 Drawing Sheets
